CLAIM

The ornamental design for a solar panel with offset opposite-side interconnect modules, as shown and described.

DESCRIPTION

FIG. 1 is a perspective view of a solar panel with opposite-side interconnect modules showing our new design;

FIG. 2 is a top plan view thereof;

FIG. 3 is a bottom plan view thereof;

FIG. 4 is a left side elevation view thereof, the right side being a mirror image;

FIG. 5 is a front elevation view thereof, the rear being a mirror image;

FIG. 6 is a perspective view thereof, shown in environmental use;

FIG. 7 is a top plan view thereof, shown in environmental use;

FIG. 8 is a bottom plan view thereof, shown in environmental use; and,

FIG. 9 is a rear elevation view thereof, shown in environmental use.

The broken lines shown are for illustrative purposes only and form no part of the claimed design.
